DRESS FORM

M. Frances Henry, San Francisco, Calif., assignor
of one-half to Utility Packages, Incorporated,
New York, N. Y., a corporation of New York

Application July 18, 1939, Serial No. 285,098

5 Claims. (Cl. 223—68)

This invention relates to dress forms, such as display forms and dressmaker forms, and has for one of its objects a dress form, including upper arms, that substantially conforms to the contour of the upper portion of a human body, and in which form said upper arms are movable in a manner and to positions, generally conforming to the manner of movement, and positions, of the arms of a person, one of which positions is with the arms extended upwardly from the shoulders so as to lie substantially within the confines of the greatest width across the body portion of the form, and another of which positions is with the arms extended downwardly and disposed outwardly of the above mentioned width across said body portion.

Another object of the invention is a dress form, including arms connected to the body of the form by pivots that support the arms for swinging about pivotal points positioned at about the same points as the pivotal points connecting the upper arms of a person with the body, and which arms, in my dress form are adapted to present substantially unobstructed, smooth and continuous, outwardly facing surfaces with the adjoining surfaces of the body of the form when the arms are swung to vertically upwardly extending and vertically downwardly extending positions so as not to injure a dress in slipping the latter downwardly onto the form or in removing the same therefrom, or to produce irregularities of a character not found in the corresponding anatomy of a person.

A still further object is the provision of a dress form that substantially conforms in shape and contour to the body of a person, including the neck, shoulders, bust, and upper arms, and in which the upper surfaces of the arm portions on the dress form is formed in outward continuation of the slope of the shoulders, and which said arm portions are pivotally connected to the body portion to swing from downwardly extending positions to vertically upwardly extending positions over the sloped portions of the shoulders with the curved upper surfaces of the arm portions positioned, generally, in the curves at the juncture of the neck and body of the form at opposite sides of the neck, but with the arm spaced from the neck.

Other objects and advantages will appear in the description and drawing annexed hereto.

Fig. 1 is a front elevational view of my dress form with the upwardly extending positions of the arms indicated in dotted lines.

Fig. 2 is a plan view of the form.

Fig. 3 is a fragmentary elevational view of the inner side of one of the arms.

Fig. 4 is a fragmentary elevational view of one of the outer, lateral sides of the body of the form. 5

Fig. 5 is an enlarged sectional view taken along line 5—5 of Fig. 2.

Fig. 6 is a plan view of the portion of the arm joint that is carried by the body, with the plate securing the same to the body being shown in 10 section.

Briefly described, the improved dress form herein described, is for use principally as a display form and dressmaker form in which the dimensions of the upper portion of the human body 15 are relatively closely followed so that the form will fill out the dress in substantially the same manner as though the dress were on the body of a person, hence, I am not concerned with the flat board forms or the like which are merely intended 20 to support dresses after the manner of clothes hangers. Heretofore, in forms of my general type, it has been impossible to slip dresses over such forms without either removing the arms, where the arms are removable, or providing a 25 relatively long placket in the side of the dress to enable slipping the dress over the shoulders of the form. In cases where the arms are first removed to place the dress on the body of the form, the operator must reattach the arms, which is 30 generally done by slipping the arms through the neck of the dress and then into the arm openings in the dress, which is inconvenient and is attended by the possibility of injury to the dress.

Attempts have been made to pivot the arms so 35 they can move to vertically upwardly extending positions, relative to the body, but the width across the shoulders generally remains substantially the same, thus requiring the excessively large placket in the side to enable placing the 40 dress on the form. This invention as disclosed in this application, overcomes the objections enumerated above, and, while a placket is generally necessary, where the circumferential dimension around the bust exceeds that of the waist, and in 45 ready-made dresses, the length of the placket is reduced to almost half by the use of my invention. It is also pertinent to note, that in display forms, it has heretofore been customary to place oversize dresses on the forms, in order to facilitate 50 placing such dresses on said forms, and the surplus resulting from the oversize is taken up by pins or the like to give the appearance of a correct fit.

In detail, the form illustrated in the drawings 55

comprises a body portion 1, arms 2 and neck 3. The body portion, including the neck, is one integral unit and the arms, of which only the upper arm portions are shown, are separate units. The 5 body and arms are shaped to conform to corresponding parts of the human body, as to cross-sectional contour, and in outline. The female form is shown, since the problems of fitting dresses on forms are not generally present in fitting men's clothing.

The body and arms of my form are hollow and are preferably made of papier-mâché for lightness, durability, and economy of manufacture, although any other suitable material may be used.

15 The arms are divided from the body along planes extending slightly convergently upwardly from points at opposite sides of the body portion that are at about the level of the busts, as indicated by lines X. Thus the upper edges of the arms and body, along the line of division are disposed appreciably inwardly from the outermost sides of the arms, and it is substantially at said upper edges that I position the means pivotally connecting and suspending the arms on the body.

20 25 The means pivotally connecting the arms to the body comprise a plate 4 secured to the upper end of each arm on the side thereof that is adjacent the body, and which plate is formed with a vertically extending, keyhole slot 5, the enlarged end 6 of said slot being lowermost. In some instances, the plate 4 may be carried on a disk of wood 7, or the like, that is fitted into the arm, as indicated in the drawing, but where the material of the arm is readily molded to provide 30 35 a strong supporting base for the plate, the material of the arm itself may be employed.

30 At each of the opposite sides of the body, and opposite to each of the plates 4, is a plate 8, which latter plate is provided with an angular 40 extension 9 adapted to extend a short distance over the upper surface of the body in direction toward the neck 3. Said plate 8 is vertically slotted at 10, said slot continuing at its upper end into extension 9.

45 The plate 4 also is formed with an extension 9' that extends over the upper surface of the arm, and slot 5 extends into said extension as indicated in Fig. 2.

Extending substantially at right angles to plate 50 55 60 65 70 75 8 and into body 1 of the form, is an elongated bracket 11. This bracket is generally of U-shape, with elongated opposed sides 12 and an end 13 connecting between the ends of said sides that are disposed within the body 1, while the sides 12 at the opposite end are formed with oppositely outwardly directed ears 14. The ears 14 are secured between plate 8 and the body at opposite sides of slot 10. The inner end 13 of the bracket is formed with a lip 15 positioned to overlie the area between said sides adjacent said end 13.

Disposed between the opposed sides 12 of said bracket, and extending longitudinally thereof, is a bar 16. Said bar 16 extends outwardly of the bracket between the open end thereof and through slot 10 in plate 8, and the end projecting outwardly of said plate is provided with a ball 17. This ball 17 is too large in diameter to pass through either slots 5, or 10, but readily passes through the enlarged end 6 of slot 5. The end of the bar 16 opposite ball 17 extends below the lip 15 and said end is threaded for a nut 18, or a pair of such nuts to insure locking such nuts in any desired position on said end.

75 Said bar 16 slidably extends through a sup-

port 19, which may be in the form of an apertured block, or a sleeve, and which support is provided with oppositely outwardly projecting stub shafts 20, or trunnions, at opposite sides thereof. The shafts 20 are rotatably supported 5 in openings in sides 12 of bracket 11, thus enabling the bar 16 with the ball 17 therein to be swung in the plane of the body in which the shoulders are both disposed, while at the same time the bar 16 may slide longitudinally relative to the axis of shafts 20.

Reacting between support 19 and nuts 18 is an expansion coil spring 21 under compression, which spring surrounds said bar 16 and constantly urges ball 17 toward plate 8. Tension 15 of said spring is regulated by adjusting nuts 18.

To attach each of arms 2 to the body, the operator merely slips ball 17 into enlarged opening 6 of slot 5, and then pulls the arm downwardly, whereupon ball 17 is disposed in the arm and engages the inner sides of the edges of the slot 5. The extension 9' on plate 4 and the lower edge of slot 10, together with engagement between lip 15 and nuts 18, all cooperate to hold the arm suspended from bar 16 in a position in which 25 the upper surface of the arm is flush, and in outward continuation of the upper surface of the body that extends outwardly from the neck, hence, when a dress is on the form, the shoulders 2' will support, and fill out the dress in substantially the same manner as when the dress is on a person.

When arms 2 are suspended in downwardly extending positions at opposite sides of the body 1, it is obvious that they may be independently 35 swung through a complete circle around bar 16 as an axis, in planes extending perpendicular to the plane in which both shoulders are disposed, and also the arms may be swung outwardly of the body in the last mentioned plane. It is this 40 last movement that is particularly important in this invention. In swinging the arms outwardly and upwardly, the upper edges of the arms, at the bends in plates 4, fulcrum on the adjacent plates 8 adjacent the bend at the junctures of 45 plates 8 and extensions 9. During the swinging movement the bars 16 pivot on the shafts 20 as the ball ends 17 swing upwardly and as the arms move to upwardly extending position the bars 16 move in slots 5, 10 across the junctures of 50 plates 4, 8 with extensions 9', 9 and into the extensions of said slots that continue into said extensions 9', 9, so that the bars 16 and arms 2 are both substantially vertically extending when the arms extend vertically upwardly, and the 55 extensions 9, 9' are substantially flattened for a short distance adjacent their junctures with plates 8, 4, which, together with the connecting bars 16, facilitate holding the arms in their upwardly extending positions, although the bars 60 alone will function to accomplish this result.

When the arms are in upwardly extending position, as above described, they are disposed within the confines of the body, and particularly are within the confines of the outermost points 65 of the lateral sides of the body, hence offer no obstruction to a dress during downward slipping of the latter over the form. Also, the arm openings in the dress will readily pass the arms 2 therethrough and after the dress is substantially 70 fully positioned on the form, the arms are swung outwardly and downwardly, where they automatically move to their normal downwardly extending positions, filling out the shoulders of the dress. It is also important to note that there 75

is a space between the neck 3, and arms 2, when the latter are in upwardly extending position, thus enabling the collar of the dress to move over the neck while the arms extend upwardly, and 5 also that the plates 4, 8 are flush with each other, when the arms are in said upwardly extending position. Since the plates 4, 8 are virtually continuations of the sides of the arms and 10 body on which they are positioned, it is apparent that said sides will form a continuous smooth surface when said arms are upwardly extending. Also when the arms hang downwardly, they are spaced from the body at about the point where the arm pits of a person would be.

15 To disconnect the arms, when the latter are suspended from the bars 16, it is merely necessary to move the arms bodily upwardly, until the ball ends 17 slip out of enlarged openings 6 at the lower ends of slots 5.

20 The plates 4, 8 may obviously be reduced in size merely sufficient to carry the slots, and a metallic form could have the slots made in the form walls themselves. Also in display forms that have painted or enameled surfaces, the 25 plates may be correspondingly painted, so that the only indication of the presence of the particular pivot means employed, would be the slots. In dressmaker forms, the usual fabric covering 26 may cover the forms, including the arms, and 30 the plates 4, 8, in such instances would cover the margins of the fabric at the juncture of the arms and body to help secure the fabric in position. The extensions 9, 9' are, of course, preferably 35 countersunk in the material of the body and arms, so as not to project from the surface thereof, and likewise the plates may be countersunk in the adjacent sides of the form and arms.

While the drawing shows only the upper portions of the body and the upper arms, it is obvious that the body may carry legs, or a supporting post, and that the arms may have the conventional joints for lower arms and hands, all of which are conventional, but in any event, the advantages of the particular invention herein 45 described are present.

Having described my invention, I claim:

1. A dress form comprising a bust portion, neck, shoulders and upper arm portions, said arm portions being normally positioned vertically at opposite lateral sides of said bust portion and terminating at their upper end surfaces substantially flush with the upper surfaces of the shoulders, means adjacent the upper end of each of the upper arm portions pivotally suspending said 55 arm portions, respectively, in downwardly extending positions from said bust portion for swinging to positions extending upwardly and over the bust portion and to within the upwardly projected area over said bust portion between said sides, said means including a pair of pivots disposed adjacent the upper ends of each of the arm portions, one pivot of each pair being secured to the

bust portion and the other pivot of each pair being secured to the upper end of one of the arm portions and means connecting the pivots of each pair.

2. In a construction as defined in claim 1, 5 means yieldably urging one of the pivots of each pair toward the other pivot of the same pair.

3. In a dress form that includes portions simulating in outline and in horizontal cross-sectional contour, the shoulders, neck, bust and upper arms 10 of a person, the outer ends of the shoulder portions of said form being formed integrally with the said arm portions and forming the upper ends of the latter, pivots swingingly suspending and supporting said arm portions from the bust 15 portion in vertical positions at opposite lateral, outer sides of said bust portion for arcuate movement of said arm portions in a single plane to inverted positions extending upwardly and over said bust portion with the upper surfaces of said 20 upper ends disposed over and facing toward the upper surfaces of the bust portion that are at opposite sides of said neck portion, said pivots being disposed adjacent said upper ends, and means supporting said pivots for arcuate movement relative to said bust portion during said 25 movement of said arm portions in said plane.

4. A dress form comprising a bust portion, a neck portion, and arm portions normally positioned substantially vertical at opposite outer 30 sides of said bust portion, the said bust, neck, and arm portions corresponding, in arrangement, with corresponding portions of the human body and being formed to substantially correspond, in breadth and thickness, to said corresponding portions, said arm portions being separate from said bust portions, and the adjacent sides of said bust portion and said arm portions, respectively, being flattened and in engagement with each other, the adjacent upper edges of said arm portions and 35 said bust portion providing fulcrums about which said arm portions are adapted to be swung upon swinging the lower ends of said arm portions in a single plane outwardly and upwardly to substantially vertical positions above and over the upper 40 sides of said bust portion that are at opposite sides of said neck portion, pivots suspending said arm portions from said bust portion for said swinging movement about said fulcrums, and means securing said arm portions to said bust 45 portion in said vertical positions at opposite outer sides of said body for swinging said arms in separate planes perpendicular to the vertical plane of said bust portion in its greatest width, which greatest width is across the body through the 50 said opposite lateral sides thereof.

5. In a construction as defined in claim 4, means yieldably holding said arm portions in engagement with said bust portion at all times during said movement of said arm portions in 55 said single plane and in said separate planes.

M. FRANCES HENRY.
